UNITED STATES PATENT OFFICE.

JOHN M. WILLIS, OF NEW YORK, N. Y.

DOCUMENTAL FILE.

SPECIFICATION forming part of Letters Patent No. 369,899, dated September 13, 1887.

Application filed May 18, 1887. Serial No. 238,610. (No model.)

To all whom it may concern:

Be it known that I, JOHN M. WILLIS, of the city, county, and State of New York, have invented a new and Improved Documental File, 5 of which the following is a full, clear, and exact description.

My invention relates to improvements in documental files in which folding front and back flaps are provided with means for binding the documents removably therein; and it has for its object to render a file of this class 10 dust, water, and animal proof, to provide it with easily-interchangeable backs to accommodate varying quantities of documents, and 15 to embody other useful features in the general structure of the file, so as to particularly adapt it for the reception and preservation of legal documents.

The invention consists in a novel construction and combination of parts, as hereinafter 20 fully described and then definitely claimed.

Reference is to be had to the accompanying drawings, forming a part of this specification, in which similar letters of reference indicate 25 corresponding parts in all the figures.

Figure 1 is a perspective view of a file embodying my improvements. Fig. 2 is a detail view of one of the interchangeable backs. Fig. 3 is a longitudinal section taken on the line $x-x$, Fig. 1.

In carrying my invention into effect I make the face and back flaps, A B, of the file of plates of equal size, formed of sheet metal—as tin—having the front and side edges curled inward to receive the stiffening-wire C, as shown. 35

The face flap, A, is made in two sections, A' A'', connected by a transverse hinge-joint, D, and the rear edge parts of the back flap, B, and of the section A'' of the face flap are bent 40 at right angles toward each other to form flanges E and F, respectively.

The flanges E and F are received snugly in opposite sides of a narrow socket, H, formed in one of the interchangeable backs G or G', the sockets in the different backs being of varying depth, so that the flaps can be adjusted at various distances apart to accommodate any thickness of the pile of documents I held therebetween. 45

I form each of the backs G G' of a straight

narrow strip of metal having its end parts returned parallel upon itself, as clearly shown in Fig. 2, the socket H, before mentioned, being thus formed between the body of the strip and its returned end parts. I also cover the 55 body of the strip with paper or fabric, J, so that indexing or classifying marks may be readily produced upon the back of each file.

The documents may be bound removably in the file by the usual fastening-studs, K, which 60 are passed upward through holes L' near the rear edges of the flaps, and through the documents, and their ends bent outward upon the fixed section A'' of the face flap in the usual way. The section A' of the face flap can thus 65 be opened to gain access to the documents, while the latter are held firmly in place; or documents may be removed or replaced at will by bending up the studs K and removing the 70 entire face flap, its flange E being withdrawn from the socket H.

For completely incasing the documents within the file thus formed, I provide a U-shaped tin or other metal strip, L, which is held edgewise between the flaps A B entirely 75 around the front and side edges of the same, with its free ends abutting against the inside of the back G at the ends thereof, and its upper and lower edges resting just inside of and against the wired edges of the flaps, which 80 edges thus form bordering-shoulders to hold the casing-strip L in place. Eyelets M are let into the front edges of the flaps A and B to receive cords N, which, when tied, hold all the 85 parts firmly together.

With this construction the documents are rendered perfectly inaccessible to dust, moisture, rats, or other destructive elements. The metallic flaps may also be covered with paper, fabric, or other suitable material. 90

Having thus described my invention, what I claim as new, and desire to secure by Letters Patent, is—

1. An adjustable documental file consisting of separable front and back flaps and a number of detachable backs of variable widths for connecting and holding said flaps at different distances apart, substantially as described. 95

2. The combination, in a file, of front and back flaps, flanges on their rear edges project- 100

ing toward each other, and a removable back socketed to receive said flanges, substantially as shown and described.

3. The combination, in a file, of the front and back flaps, A, B, adapted to fold together and having inwardly-projecting shoulders on their front and side edges, a back, G, connecting the rear edges of said flaps, and an incasing-strip, L, held between the said flaps, with

its free ends abutting against the said back G 10 and its upper and lower edges resting within and in contact with said shoulders, substantially as shown and described.

JOHN M. WILLIS.
